CONTROL DEVICE FOR STARTING WINDINGS OF SPLIT-PHASE INDUCTION MOTORS

Howard W. Ecker, St. Paul, Minn.

Application November 5, 1947, Serial No. 784,158

5 Claims. (Cl. 318—221)

1

My invention relates to control devices for starting windings of split phase induction motors and has for an object to provide a device operable independently of centrifugal force.

Another object of the invention resides in providing a control device which may be positioned remotely from the motor, permitting the motor to be encased within a sealed compartment.

A still further object of the invention resides in providing a device operable by virtue of the change in phase angle between the currents in the running winding and starting winding of a split phase motor.

Another object of the invention resides in providing a core structure having three legs preferably arranged in the form of an E and including an armature pivoted about an axis disposed in proximity to the center leg and having two branches one adapted to be attracted by the pole on one outer leg and another branch adapted to be attracted by the pole on the other outer leg, one of said branches moving toward the pole of the corresponding leg and the other moving from the pole of its corresponding leg and vice versa as the armature swings about its pivot.

An object of the invention resides in providing a winding on the center leg adapted to be energized by the current in the running winding of the motor and producing magnetic flux through two paths, one including one of the outer legs and the other including the other of the outer legs.

Another object of the invention resides in providing a winding on the first named outer leg producing flux opposing the flux in said leg produced by the first named winding.

A feature of the invention resides in providing a switch operated by the armature and adapted to be opened when the armature is attracted by the third leg, said switch serving to de-energize the starting winding.

Other objects of the invention reside in the novel combination and arrangement of parts and in the details of construction hereinafter illustrated and/or described.

In the drawings:

Fig. 1 is an elevational part sectional view of a control device for starting windings of split phase motors illustrating an embodiment of my invention.

Fig. 2 is a plan view of the structure shown in Fig. 1.

Fig. 3 is a plan section view taken on line 3—3 of Fig. 1.

2

Fig. 4 is a wiring diagram showing the use of my invention with a split phase motor.

Fig. 5 is a diagrammatic curve illustrating the relation between the currents in the starting and running windings of a split phase motor.

My improved control device consists of a core structure 10 which includes three legs 11, 12 and 13, mounted on a yoke or connection portion 14. This core structure is so arranged that the same is substantially E-shaped in form with the two legs 11 and 13 outermost, and the leg 12 at the center between the same. The legs 11 and 13 are formed with ends 15 and 16 which serve as poles for the said legs of the core structure.

15 The leg 12 of the core structure 10 has an extension 17 which extends through a bracket or support 18 and which is riveted over to hold the said bracket securely attached to the hold. A groove 19 extends across the said bracket and 20 forms two corners 21 and 22 which serve as fulcrums for an armature 23. This armature has two branches 24 and 25 which extend over and are adapted to be attracted by the poles 15 and 16. Two screws 26 extend through the armature 23 and are threaded into the bracket 18. Coil springs 27 encircle these bolts and are seated at their lower ends against the armature 23 and at their other ends against nuts 28 screwed upon said screws. The two branches 24 and 25 30 of the armature 23 form a slight angle with one another so that the connecting portion 29 of said armature is slightly rounded and rests upon the support or bracket 18 merely at the two corners forming the fulcrums 21 and 22. Springs 35 27 engaging the armature 23 hold the portion 29 of said armature in engagement with the said fulcrums as clearly shown in Fig. 1. The armature is so designed that when in such position the air gap 31 between the branch 24 and pole 40 15 is very slight while the air gap 32 between the pole 16 and branch 25 is considerably greater. Shims 30 on the armature 23 prevent the same from sticking to the poles 15 and 16.

Mounted on the leg 12 of core 10 is a winding 45 33 which is adapted to be energized by the current in the running winding of the motor with which the device is to be used. On the leg 11 is a similar winding 34 adapted to be energized by the current in the starting winding of the motor. It will be readily comprehended that the winding 33 produces magnetic flux in the leg 12 which passes through two paths, one including the leg 11, air gap 31 and branch 24 of armature 23, and the other which includes the leg 13, 50 air gap 32 and the branch 25 of armature 23.

The leg 13 at the locality of the pole 16 is formed with a transverse slot 62. In this slot is disposed a ring of copper or some other nonferrous conducting material which encircles a portion 63 of said pole and serves as a shading coil for causing positive attraction of the armature 23 by said pole when the branch 25 is brought into proximity thereto.

Formed on the bracket 18 is an arm 35. This arm has attached to it a bar 36 of insulating material which is provided with a contact 37 forming one element of a switch 38. The end of the branch 25 of armature 23 has attached to it a bar 39 of insulating material which again is provided with a contact 41 forming the other element of said switch. The contact 37 is mounted on a threaded stem 42 which is screwed into the insulating bar 36. This contact may be adjusted with reference to the contact 41 by means of an adjusting nut 43 screwed on said stem. A second nut 44 on said stem serves to attach a conductor to the contact. A similar flexible conductor, not shown, is attached to the contact 41 by soldering or otherwise.

For the purpose of illustrating the invention, I have shown diagrammatically in Fig. 4, a certain split phase capacitor induction motor 45. This motor has a rotor 46, a running winding 47, a starting winding 48 and a capacitor 49. The two windings 47 and 48 are connected together and to a common conductor 50 which in turn is connected to one side of a line switch 51. The other end of the winding 48 is connected by means of a conductor 51 to the capacitor 49. The ends of the two windings 33 and 34 are connected together and to a conductor 52 which in turn is connected to the other side of the switch 51. The switch 51 is further connected to a source of alternating current which has been diagrammatically indicated as a line 53. The other side of the running winding 47 is connected by means of a conductor 54 to the other end of the winding 33. The other end of the winding 34 is connected by means of a conductor 55 to the movable contact 41 on armature 23. The fixed contact 37 of this switch is connected by means of a conductor 56 to the capacitor 49 of the motor 45.

In Fig. 5, I have shown a curve illustrating the relation between the phase angle of the currents passing through the starting winding and the running winding of the particular motor 45. The curve 58 is the curve for the starting winding and the curve 59 is the curve for the running winding. It will be noted that the phase angle for the starting winding is leading at low speeds and that the phase angle for the running winding is lagging at low speeds. It will be further noted that the phase angle of the currents in the two windings becomes substantially equal when the two curves cross which is at substantially 80% of synchronous speed for this particular motor.

The theory of operation of the invention is as follows: The armature 23 is normally in the position shown in Fig. 1 with the air gap 31 small, and the air gap 32 large and with the switch 38 open. At the moment the switch 51 is closed, the running winding 47 is energized. This causes flux to flow through both the legs 11 and 13 of core 10. Air gap 31 being of lesser length than air gap 32, the branch 24 of armature 23 is attracted to pole 15 and the switch 38 closes. During such movement the armature rocks on fulcrum 21. Closure of the switch 38 energizes

winding 34. Windings 33 and 34 now both produce magnetic flux. The flux from winding 33 passes through the legs 11, 12 and 13 of the core structure. The flux from the winding 34 passes mostly through the legs 11 and 12. The windings 33 and 34 are so connected that the flux from the said windings in leg 11 opposes one another. At low speeds the phase angle between these fluxes is substantial and the said fluxes add vectorially to produce a resultant flux having greater attractive force on the branch 24 of armature 23 than the attractive force exerted on branch 25 of said armature by the portion of the flux produced by winding 33 and passing through the leg 13 and air gap 32. As the motor picks up speed the difference in phase angle between the two fluxes becomes less and less until the fluxes from the said windings become substantially in phase which occurs when the speed of the motor is substantially 80% of synchronous speed. At such time, the attraction of the pole 15 for the armature branch 24 substantially ceases since the two fluxes produced by the windings 33 and 34 in the leg 11 substantially cancel out. At this time the flux from winding 33 through the leg 13 is sufficient to cause the pole 16 to attract the branch 25 of armature 23 and to swing the said armature away from pole 15. This opens switch 38 and de-energizes the starting winding 48. Only the flux produced by winding 33 is now effective. However, the air gap 32 has now become small and the air gap 31 has increased so that the branch 25 of the armature is held attracted to the pole 16 with only normal no load current flowing in the winding 33. In the movement of the armature to such position the same rocks on the fulcrum 22. Upon opening of the switch 51 winding 47 becomes de-energized and the spring 27 returns the armature 23 to its normal position shown in Fig. 1. The parts are thus reset and the motor is ready to be started again. In the event that the motor speed is reduced to less than 80% speed switch 38 will not be closed unless the motor is de-energized, thus preventing energization of the starting winding and possible burning out of the same.

While I have shown the switch 38 as normally open it can readily be comprehended that the contact 37 may be adjusted to cause the same to be normally closed. In such case, dynamic braking of the motor results and the rotor of the motor is quickly brought to rest.

The advantages of my invention are manifest. By means of my invention the starting winding control device can be placed exteriorly of the motor, thus permitting of the insertion of the motor within a sealed case and eliminating the use of pressure seals. My improved device is independent of time and will not operate to de-energize the starting winding until the motor gets up to its desired speed. The device can be constructed at a relatively economical cost. Due to the fact that there is a considerable difference in phase angle between the currents in the starting and running windings at low speeds my device becomes positive in action and will reduce failure to start to a minimum. The device will operate satisfactorily on wide variation in line voltage. Contacts 38 can be set normally closed and thus accomplish dynamic braking when capacitor type motors are used. The device in the form shown will not reconnect the starting winding in case of an overload.

With my invention the starting winding con-

tacts are readily accessible for cleaning and replacement whenever the occasion requires it.

Changes in the specific form of my invention, as herein described, may be made within the scope of what is claimed without departing from the spirit of my invention.

Having described my invention, what I claim as new and desire to protect by Letters Patent is:

1. A relay for use with a split phase induction motor having a running winding and a starting winding and in which the phase angle between the currents in the running winding and starting winding is greatest at low speeds and approaches zero at a higher speed, said relay comprising a magnetic core structure, having three legs provided with poles, an armature pivoted for swinging about an axis disposed in proximity to the pole of one of said legs and movable toward the pole of another leg and from the pole of the third leg and vice versa, a switch operable by said armature and moved into operative position upon movement of the armature toward the pole of said second leg, a winding on said first leg adapted to be energized by the current in said running winding, a winding on said second leg adapted to be energized by the current in said starting winding, said windings being connected to procure operation of said switch when the phase angle between the currents in said running and starting windings approaches zero to cause said switch to de-energize said running winding.

2. A relay for use with a split phase induction motor having a running winding and a starting winding and in which the phase angle between the currents in the running winding and starting winding is greatest at low speeds and approaches zero at a higher speed, said relay comprising a magnetic core structure, E-shaped in form and having three legs provided with poles, an armature pivoted for swinging movement about an axis disposed in proximity to the pole of the center leg, said armature having a branch movable toward the pole of one of the outer legs and another branch movable from the pole of the other outer leg and vice versa, a winding on said center leg adapted to be energized by the current in said running winding, a winding on the first named outer leg adapted to be energized by the current in the starting winding and producing a flux opposing the flux produced in said leg produced by said first named winding, and a switch adapted to be connected to the starting winding and having a part movable with the branch of said armature acting with the third leg of said core structure, said branch upon movement toward said third leg opening said switch and when attracted by said third leg holding said switch open until de-energization of the winding on the center leg.

3. A relay for use with a split phase induction motor having a running winding and a starting winding and in which the phase angle between the currents in the running winding and starting winding is greatest at low speeds and approaches zero at a higher speed, said relay comprising a magnetic core structure, E-shaped in form and having three legs provided with poles, an armature pivoted for swinging movement about an axis disposed in proximity to the pole of the center leg, said armature having a branch movable toward the pole of one of the outer legs and another branch movable from the pole of the other outer leg and vice versa, a winding on said center leg adapted to be energized by the current in said running winding, a winding on the first named outer leg adapted to be energized by the current

in the starting winding and producing a flux opposing the flux in said leg produced by said first named winding, and a switch adapted to be connected to the starting winding and having a part movable with the branch of said armature acting with the third leg of said core structure, said branch upon moving toward said third leg opening said switch, and resilient means for normally holding said switch in open position and said branches spaced from said poles, the distance of said first named branch of said armature from its pole being less than the distance of said second named branch of said armature from its pole.

4. A relay for use with a split phase induction motor having a running winding and a starting winding and in which the phase angle between the currents in the running winding and starting winding is greatest at low speeds and approaches zero at a higher speed, said relay comprising a magnetic core structure, E-shaped in form and having three legs provided with poles, an armature pivoted for swinging movement about an axis disposed in proximity to the pole of the center leg, said armature having a branch movable toward the pole of one of the outer legs and another branch movable from the pole of the other outer leg and vice versa, a winding on said center leg adapted to be energized by the current in the running winding and producing magnetic flux passing through two paths, one of said paths including the first named outer leg and the other including the second named outer leg, a winding on the first named outer leg adapted to be energized by the current in the starting winding and producing flux in said leg opposing the flux produced in said leg by the center leg winding, said fluxes cancelling one another as the phase angle between the currents in said winding approaches zero and releasing said armature for movement toward the second outer leg to open said switch.

5. A relay for use with a split phase induction motor having a running winding and a starting winding and in which the phase angle between the currents in the running winding and starting winding is greatest at low speeds and approaches zero at a higher speed, said relay comprising a magnetic core structure, E-shaped in form and having three legs provided with poles, a winding on the center leg adapted to be energized by the current in said running winding, a winding on one of said outer legs adapted to be energized by the current in the starting winding and producing a flux opposing the flux in said leg produced by said first named winding, an armature extending across said poles and having branches adapted to be attracted by the outermost poles, two spaced parallel fulcrums for said armature disposed at the locality of the center pole and supporting said armature with the branch adjacent said first named outer pole spaced from but close to said pole and the other branch spaced from and remote from the other outer pole, resilient means for holding said armature against both of said fulcrums and a switch carried by said armature and adapted to be connected to the starting winding circuit and open when the armature is in normal position, said switch being adapted to be closed by said armature when said first named branch of the armature is attracted by said first named outer pole and remaining open when the second named branch is attracted by the second named outer pole.
